[57] CLAIM

The ornamental design for a golf tee, as shown and described.

DESCRIPTION

FIG. 1 is a front elevational view of a golf tee showing my new design;

FIG. 2 is a left side elevational view thereof;

FIG. 3 is a right side elevational view thereof;

FIG. 4 is a rear elevational view thereof;

FIG. 5 is a bottom plan view thereof;

FIG. 6 is a top plan view thereof;

FIG. 7 is a side elevational view of a golf tee showing a second embodiment being rotated slightly counter clockwise;

FIG. 8 is a front elevational view thereof, the rear and sides being substantially identical;

FIG. 9 is a top plan view thereof;

FIG. 10 is a bottom plan view thereof;

FIG. 11 is a front elevational view of a golf tee showing a third embodiment;

FIG. 12 is a left side elevational view thereof;

FIG. 13 is a right side elevational view thereof;

FIG. 14 is a rear elevational view thereof;

FIG. 15 is a bottom plan view thereof; and

FIG. 16 is a top plan view thereof.
